UNITED STATES PATENT OFFICE

2,332,095

APPARATUS FOR CLEANING VALVES

William McGibbon, Glasgow, Scotland

Application April 7, 1941, Serial No. 387,344
In Great Britain April 29, 1940

3 Claims. (Cl. 51—15)

This invention relates to improvements in or modifications of apparatus for removing carbon deposit from the valves of internal combustion engines as set forth in the specification of my co-pending United States Patent application Serial Number 302,615, filed November 2, 1939, which matured as Patent No. 2,272,686, Feb. 10, 1942.

In the aforesaid, means are provided for rotating the valve on its axis and separate means for swivelling a nozzle the discharge from which is directed on to the face and neck of the valve.

According to the present invention, a common operating means is provided whereby the valve is rotated on its axis simultaneously with the swivelling action of the nozzle which deals with the face and neck.

Thus, and in the general method of carrying the invention into effect, the means which rotates the valve with its stem on the axis of this latter (when the valve is mounted in position) through intergearing or otherwise brings into action the means for moving the nozzle concerned with cleaning the face and neck of the valve.

This means may include toothed gearing or belt gearing or otherwise which preferably has a reduction ratio. As a consequence thereof the valve to be cleaned may be rotated on its axis a desired number of times during the traverse of the spraying and cleaning action of the jet from the nozzle cooperating with the neck and the face of the valve, whilst the off-centre nozzle remains in action for its jet to clean the crown of the valve.

In order that the invention may be better understood, it will now be described with reference to the accompanying drawings, which are given by way of example only and in which:

Fig. 1 shows an exterior elevation of one form of apparatus constructed according to the invention.

Fig. 2 shows a sectional plan through the axis of rotation of the valve, and

Fig. 3 shows a side elevation of Fig. 1.

In the particular method of carrying the invention into effect shown in the drawings, a generally rectangular main casing 4 is provided, open at the top and closed at the bottom except possibly in a position for the escape of the cleaning particles (shot or the like). This casing is provided with a cover 6 (preferably as shown of somewhat truncated pyramidal form) which may or may not include a window such as 7 with or without an illuminating lamp such as 8.

Further, this cover is hinged at one edge at 9 and has a clip 10 on another edge to facilitate

the opening and the placing in position of the valve 11 with its stem 12 to be cleaned.

Within the main chamber formed by the casing 4 there are disposed the two main nozzles 13 and 14 together with their connections, the one 13 being fixed and disposed to come slightly off the axis of the valve and stem to be cleaned (when mounted in position), its jet being directed to the crown thereof, the other 14 being so mounted that it can have a swivelling action and disposed so that its jet is directed to the neck and face of the valve (when mounted in position).

Exterior of the main casing and attached to one side thereof there is provided an additional housing 15 which includes a bearing or journal 16 to receive a sleeve 17 constituting the exterior of a chuck. At one end this sleeve projects into the interior of the main casing 4, where its exterior diameter is reduced at 18 and has a screw thread formed thereon. This latter receives a cap-like nut 19 having a central aperture for the passage of the stems 12 of the valves 11 to be cleaned.

The sleeve 17 has on its interior and adjacent 25 the nut a number of packing washers 20 followed by a series of axially and radially expandable and contractible rubber washers 21 (as shown) or a corrugated rubber sleeve having similar properties could be utilised. These washers 21 or this sleeve are abutted at the end remote from the packing washers 20 by the open end 22 of a hollow cylinder 23 having the other end 24 closed and being slidably mounted in the end 25 of the exterior sleeve 17 of the chuck.

This end 25 of the chuck sleeve is closed and has an exterior flange 26 which abuts a partition 27 extending across the exterior housing 15. This closed end 25 is formed with an apertured boss 28 to which is secured a hand-wheel 29 for rotating the sleeve 17 in the bearing or journal 16 and the central spindle 30 is bored for the passage of a clamping rod 31 screwthreaded towards the exterior and terminating in a clamping handle 32. This screwed rod 31 on the interior abuts the closed end 24 of the sliding cylinder 23 and consequently by turning the clamping handle 32 this sliding cylinder compresses the rubber washers 21. This compression action causes the said washers to grip the stem 12 of the valve 11 when the same has been inserted in position. Similarly, by releasing the clamping means, the said stem readily can be removed.

The partition 27 in the housing 15 also has a bearing or boss 33 for a gear wheel or pulley 34 of comparatively large diameter which meshes

with a smaller gear wheel or pulley 35 on the boss of the chuck sleeve 17.

The spindle of the larger wheel 34 carries on the interior of the housing a cam 36 of suitable form with which co-operates one arm 37 of a spring-returned follower mounted on a vertical spindle 38 the other arm 39 being attached to the swivelling nozzle 14. In this manner when the chuck is turned to rotate the valve and stem 11-12 the said nozzle 14 is caused to swivel.

If desired, the exterior of the chuck sleeve 17, which rotates in its bearing or journal 16, may, as shown, be channelled or grooved at 40 to receive a suitable lubricant through a greasing nipple or the like 41.

In the drawings there are indicated air vents 42 in the casing 4 guarded by a filter 43. In place of such a device, however, a bag may be substituted.

Although a particular mechanism has been described for effecting the rotational movement of the valve and the swivelling action of the nozzle, it will be understood that the invention is not limited thereto as this combined action may be carried out in a great variety of manners.

What I claim and desire to secure by Letters Patent of the United States of America is:

1. In an apparatus for removing carbon deposit from valves, the combination of a housing, a nozzle movably located in the housing, a secondary housing adjacent said first named housing, a support for the valve to be cleaned in said secondary housing, said support being arranged to project a portion of the valve into the first named housing, clamping means for said valve in said

support, means on the outside of the secondary housing for rotating the clamping means and imparting movement to the nozzle, and additional means supported by said first named means for actuating said clamping means to fix and release said valve respectively.

2. In an apparatus for removing carbon deposit from a valve, the combination of a housing, a nozzle oscillatable within said housing, a secondary housing, a support for the stem of the valve to be cleaned in said secondary housing, said support being adapted to maintain said valve in the plane of oscillation of said nozzle, means for oscillatably supporting said nozzle in said secondary housing, clamping means for the valve stem in said support, manually operable means for rotating the valve and for imparting oscillating movement to the nozzle, and means supported by said first named means for clamping and releasing the valve stem in said support.

3. In a device for removing carbon deposit from a valve, the combination of a housing, a nozzle oscillatable in said housing, a secondary housing, a support in said secondary housing for holding a valve with the portion to be cleaned in said first named housing in the plane of oscillation of said nozzle, means accessible from the exterior of both housings for imparting a rotary movement to the valve and simultaneously imparting oscillatable movement to the nozzle, said means comprising a hand wheel associated with the support for the valve, and clamping means in the plane of the hand wheel for clamping and releasing the valve in its support.

WILLIAM McGIBBON.
